UNITED STATES PATENT OFFICE.

DAVID R. SHIRAS, OF PITTSBURGH, PENNSYLVANIA.

BORING TOOL.

Application filed March 29, 1927. Serial No. 179,280.

This invention is a tool to facilitate the installation of the silage-ejecting device disclosed in Letters Patent, No. 1,543,525, issued to me June 23, 1925. In said patent, 5 there is disclosed a mechanism for ejecting silage from a silo and consisting of a shaft supported in the lower end of the silo and equipped with propellers whereby rotation of the shaft will eject the silage through the 10 usual discharge opening formed in the side of the silo. In building new silos, it is a simple matter to install the said silage ejecting mechanism but some difficulty has been found in applying said ejecting mechanism 15 to silos already existing and in use, and the object of the present invention is to provide a simple and inexpensive tool which may be easily operated to cut through stored silage and permit removal of a portion of the same 20 so as to provide a space in which the ejector may be mounted. The invention is illustrated in the accompanying drawing and will be hereinafter fully set forth.

In the drawing:

25 Figure 1 is a sectional elevation showing the lower end of a filled or partially filled silo with my improved tool applied thereto in operative position, and

30 Fig. 2 is a detail perspective view of the tool removed from the silo.

The silo, indicated at 1, may be of any approved type and is shown as provided with an opening 2 at one side to accommodate the bearing for the silage-ejecting shaft 35 and at a diametrically opposite point with a discharge opening 3, the discharge opening in practice being normally covered by an air-tight door which has been omitted from the drawing in order to more clearly illustrate the present invention. My improved boring tool consists of a cylindrical tube 4 of proper diameter to be inserted through the discharge opening 3 and fit closely but rotatably therein. This tube 4 is provided 40 at one end, which is the outer end when the device is in use, with openings 5 through which a lever member 6 may be engaged to impart turning movement to the tube. The opposite end of the tube is sharpened so that 45 it will readily cut through the silage and it may be equipped with teeth 7 in the manner of a circular saw. While I have shown these teeth, however, it is to be understood that the device will operate efficiently with 50 the edge merely sharpened, but I prefer the teeth as I believe the action is more rapid. The tube is also provided with a longitudinal slot 8 opening through the ends of the tube for a purpose which will presently appear. The tube will ordinarily be constructed 55 of material which will retain its form and any tendency to expand will be resisted by the wall of the opening through which it is inserted and by the pressure of the silage at its sides. If preferred, however, a web of 60 material may be left across the outer end of the slot. When the device is in use, the outer portion thereof may be supported in any desired manner, as by a prop 9, placed a suitable distance from the silo and upon 65 which the tool may rest so that it will be supported with its axis at a right angle to the vertical axis of the silo. It will be understood that silos are usually built with the discharge opening 3 but 70 ordinarily without the opening 2. It will also be understood that withdrawing silage by pulling or raking it through the discharge opening is laborious and unsatisfactory and that the ejecting mechanism disclosed in my aforesaid Letters Patent effects 75 discharge of the desired quantity of silage easily, rapidly and without wasteful scattering. It will be now assumed that it is desired to install the ejecting mechanism in 80 a silo which is not equipped with any ejecting mechanism and is filled or partially filled with silage. The opening 2 is bored in the wall of the silo at a point diametrically opposite the discharge opening, its 85 location being preferably determined by external measurement before the cutting tube 4 is brought into service. The tubular boring tool is placed with its cutting end in the discharge opening 3 and its 90 outer portion may be supported by a prop 9. Sufficient force is applied to the lever 6 to turn the tool and cause it to cut through the silage and this operation is continued 95 until the tool abuts the far wall of the silo. The lever handle 6 may then be withdrawn so that the core of silage which has been taken into the tube may be drawn out in any convenient manner through the slot and the outer end of the tube. The tube will 100 now be serving as a support for the remaining silage and its interior will be clear. If the slot 8 is not then at the bottom of the tool, the tool is given a part rotation so as to bring the slot into the lowest position, 105 whereupon the silage-ejecting shaft with the propelling ejectors thereon and a proper

supporting bracket may be inserted end-
wise through the outer end of the tool and
placed in the proper position in the silo,
with the end of the shaft projecting through
5 the opening 2 to be equipped with a crank
or other operating element and the bearing
bracket passing through the slot to rest on
the bottom of the silo. The diameter of the
boring tool will be such that sufficient ac-
10 cessibility will be furnished to permit secur-
ing devices to be manipulated whereby the
bearing bracket for the silage-ejecting shaft
may be secured upon the bottom of the silo.
The tubular tool may then be easily drawn
15 out from the silo, leaving the ejector in op-
erative position therein. Thereafter, when
silage is to be used, the desired quantity
may be quickly obtained by operation of the
ejector. In withdrawing the tool, the longi-
20 tudinal slot obviously permits the tube to
slide past the bearing bracket to the ejector.

From the foregoing description, it will

be seen that I have provided an exceedingly
simple, inexpensive and convenient tool
whereby a silage ejector may be installed in 25
a silo which is in use.

Having thus described the invention, I
claim:

A boring tool for use in placing an ejector
in a filled silo having a discharge opening 30
and a diametrically opposite opening to re-
ceive the ejector shaft, said tool consisting
of a cylindrical tube adapted to rotatably
fit within the discharge opening of the silo
and open at both ends with its leading end 35
forming a silage cutter and constructed at
its trailing end to be engaged by a turning
element and having a longitudinal slot open-
ing through its leading end whereby to per-
mit emplacement of an ejector in the silo 40
and withdrawal of the tool past the ejector
to leave the ejector in the silo.

In testimony whereof I affix my signature.

DAVID R. SHIRAS. [L. s.]
